TENNIS TARGET

Thomas E. Clemons, Sr., Rte. 11, Box 826,
Greensboro, N.C. 27410

Filed Oct. 10, 1973, Ser. No. 405,069

Term of patent 14 years

Int. Cl. D21—01

U.S. Cl. D34—5 PP

FIG. 1

FIG. 2

FIG. 3

FIG. 4

FIG. 5

FIG. 7

FIG. 6

FIG. 1 is an elevational view of one side of a tennis target embodying my new design, and illustrating the tennis ball receiving opening;

FIG. 2 is an elevational view of one end of the tennis target, the opposite end being substantially identical thereto;

FIG. 3 is an elevational view of the side of the tennis target opposite to that of FIG. 1;

FIG. 4 is a top plan view;

FIG. 5 is an end elevational view of the tennis target supported in a different position;

FIG. 6 is a perspective view of the tennis target; and

FIG. 7 is a bottom plan view.

I claim:

The ornamental design for a tennis target, as shown and described.
